UNITED STATES PATENT OFFICE.

WILLIAM THOMAS COULSON, OF PENGE, ENGLAND.

LENS.

1,081,215.

Specification of Letters Patent.

Patented Dec. 9, 1913.

Application filed September 17, 1910. Serial No. 582,496.

To all whom it may concern:

Be it known that I, WILLIAM THOMAS COULSON, a subject of the King of Great Britain, residing at Penge, England, have 5 invented new and useful Improvements in Lenses, of which the following is a specification.

This invention relates to that class of lamp lens in which the reflection from the 10 internal surface of the glass is utilized.

The lens consists of a truncated cone or conoid of glass or other suitable substance pierced by a hole the axis of the cone and the hole being coincident. The illuminant 15 is placed in the central hole. The slant surface of the cone or conoid forms the reflector. The contours of the conic surface, the base or front of the lens and the central hole may vary considerably to suit different 20 conditions.

The following are examples:—Figure 1 gives an axial section of a form in which the conoid reflecting surface is spherical or parabolic the base or front indented with 25 circular steps and the hole cylindrical. Fig. 2 shows a form in which the steps are reduced to a slanting or conical surface. Fig. 3 shows a form in which the slant is leveled so that the front of the lens becomes flat.

30 In each Figs. 1, 2 and 3 the axis of the lens lies within the cutting plane making the section.

It is found advisable in some cases to manufacture the lens in two or more sections, the 35 planes of cleavage preferably containing the axis of the lens. A front elevation of one such arrangement is shown in Fig. 4 and one portion or section in Fig. 5.

40 For ease of manufacture or other reason it might be advisable to modify the shape of the sections; for example they might be constructed with plane surfaces only. Such a lens is shown in front elevation in Fig. 6, and a single section of it in Fig. 7.

45 Suitable means may be employed to secure the sections in their relative positions and the whole lens whether in one piece or in sections may be suitably inclosed. Many kinds of illuminant may be employed, perhaps electric glow lamps and incandescent coal gas burners are among the most suitable.

50 Fig. 8 is a diagrammatic view illustrating one way in which the invention may be utilized practically. In this instance, I represents an illuminating device which may be

of any suitable form. This illuminating device is placed within the axially-arranged hole in the lens and the direct light rays a from the illuminating device proceed to the 60 surface x of the lens which surface acts as a reflector whereby the reflected rays a' are directed forwardly. In this figure of the drawing, the illuminating device is so placed with reference to the lens surface x that the 65 reflected rays a' will be arranged substantially in parallelism. It will be obvious, however, that by shifting the illuminating device 1 rearwardly or toward the lens surface x , the reflected rays a' will diverge as 70 they proceed from the lens and, conversely, by shifting the illuminating device 1 forwardly or in a direction from the lens surface x , the reflected rays a' will converge as 75 they proceed from the lens. Any desired degree of divergence or convergence of the reflected rays can be obtained by suitably adjusting the position of the illuminating device in the axial hole of the lens.

The invention may be used advantageously as a reflector for lamps of various kinds, the rear surface of the lens acting as a reflector. This surface of the lens is protected and avoids the necessity of frequent cleaning as is necessary when ordinary 85 mirrors are used and, moreover, the mass of the lens is such that it will be capable of 90 withstanding most shocks that would break or damage ordinary mirrors.

What I do claim as my invention and desire to secure by Letters Patent is:—

1. A lens reflector the body of which is provided with a hole extending entirely therethrough to accommodate an illuminating device and operative to project light 95 rays in parallelism therefrom.

2. A lens reflector having a hole extending axially therethrough to accommodate an illuminating device and operative to project light rays in parallelism therefrom.

3. A lens reflector having a hole extending therethrough coincident with the optical axis of the lens to accommodate an illuminating device and operative to project light rays in parallelism therefrom.

4. The combination of a lens having a hole extending axially therethrough, and an illuminating device positioned in said hole, the rays from the illuminating device being reflected in parallelism by a surface of the 110 lens.

5. A lens reflector composed of a plurality

of sections united on planes which intersect the axis of the lens, the latter being provided with a hole which extends axially therethrough, and the lens being operative to project light rays in parallelism from an illuminating device located in said hole.

In testimony whereof I have hereunto set

my hand in presence of two subscribing witnesses.

WILLIAM THOMAS COULSON.
